R. MURDOCH.

Running-Gear.

No. 15,189.

Patented June 24, 1856.

UNITED STATES PATENT OFFICE.

RICHARD MURDOCH, OF BALTIMORE, MARYLAND.

IMPROVEMENT IN THE RUNNING-GEAR OF CARRIAGES.

Specification forming part of Letters Patent No. **15,189**, dated June 24, 1856.

To all whom it may concern:

Be it known that I, RICHARD MURDOCH, of the city of Baltimore, and State of Maryland, have invented a new and useful Improvement in Running-Gear of Vehicles; and I do hereby declare that the following is a full, clear, and exact description of the construction and operation of the same, reference being had to the annexed drawings, forming part of this specification, in which—

Figure 1 is a side elevation of my improved running-gear. Fig. 2 is a plan. Fig. 3 is a plan showing short axles in oblique position. Fig. 4 is a vertical section on *xx*. Fig. 5 is a vertical section on *yy*.

Similar letters of reference in the several figures denote the same parts.

The nature of my invention consists in connecting the inner ends of short independent axles with boxes sliding upon a swivel-bar, in order to give the requisite strength to the system, and at the same time admit of the free movement of the said axles about their attachment; and, further, my invention consists in making this attachment of a bolt perpendicular to the axle, and passing through the same and the permanent cross-bar of the forward portion of the running-gear. The details of construction and operation are as follows:

In the drawings, *W W* are the wheels, *B* the rear axle, *C* the fore cross-bar, and *D* the pole, of the vehicle. The fore wheels are mounted upon the short axles *a a*, on whose inner extremities are boxes *b b*, capable of sliding upon a bar *c*, which is movable about the axis of the bolt *d*. These axles are attached to the extremities of the cross-bar *C* by bolts *e*, passing through the axle and brace-lever *f*, as shown in Fig. 5. The inner extremities of the axles are attached to the boxes *b* by a loose connection *i*, which permits the free movement of the box along the bar as the axle is turned about its attachment to cross-bar *C*.

The portion of the axle *a* through which the bolt *e* passes is embraced by the brace-lever *f* and strap *g*, secured by bolts *h*, as shown in Fig. 5. The lever-braces *f* are connected with each other and with the tongue *D* by bar *l*, bolts *m* uniting these parts. By this con-

nection of the pole *D* with the lever-braces *f* the movement of the axles is produced, the swivel-bar *c* turning with the movement of the axles, as shown in Fig. 3. By this connection of the inner ends of the axles with the bar *c* the axles are supported in every position they may assume with the bracing requisite to insure the strength of the system. This obviates the necessity for stationary ways to support the ends of the axles in their travel, and gives the strength which is wanting in those constructions where the ends of the axles are left unsupported, thus combining the strength of the former and the free motion of the latter construction.

The bolt-connection gives a simple mode of attaching the axle to the cross-bar, which is easily renewed when from wear the connection becomes loose.

The swivel-bar *c* is connected with bolt *d* by being let into a cylindrical piece *n*, secured to plate *p*, in which bolt *d* is fixed, as shown in Fig. 4, the upper portion of bolt *d* passing through the stationary plate *q* and cross-piece *C*. This connection may be varied in any manner which will permit a free movement to the bar *c*.

I disclaim the short axles and the manner of turning them about their attachments, such constituting no part of my invention. I also disclaim supporting the extremities of the axles on stationary tramways during their movement; but

What I do claim as new and of my own invention, and desire to secure by Letters Patent, is—

The swivel-bar *c* and boxes *b b*, in combination with the short axles *a a*, connected with the extremities of the cross-bar, substantially as described, operating as and for the purposes specified.

In testimony whereof I have hereunto signed my name before two subscribing witnesses.

RICHARD MURDOCH.
